(57) **CLAIM**

The ornamental design for a fishing lure, as shown and described.

DESCRIPTION

Disclosure Document No. 499668 was received by Petitioner on Sep. 7, 2001 and requested to be acknowledged in this application for Patent.

FIG. 1. is a front elevation view of a fishing lure showing my new design;

FIG. 2. is a rear elevational view thereof;
FIG. 3. is a right side elevational view thereof, the left side being a mirror image;

FIG. 4. is a top plan view thereof;

FIG. 5. is a bottom plan view thereof;

FIG. 6. is an enlarged front perspective view for further dimensional clarification of my new design; and,

FIG. 7. is an enlarged front perspective view for further dimensional clarification of my new design.
